United States Patent Office

Des. 181,416
Patented Nov. 12, 1957

181,416

FAN

Elmer S. Hewitt, Wilmette, Ill.

Application March 23, 1956, Serial No. 40,746

Term of patent 3½ years

(Cl. D26—7)

Figure 1 is a perspective view of a fan embodying the new design;

Figure 2 is a front elevational view thereof;

Figure 3 is a side elevational view thereof; and

Figure 4 is a top plan view thereof.

The rear of the fan is conventional in construction.

I claim:

The ornamental design for a fan, as shown and described.
